LATCHING DEVICE FOR COLLAPSIBLE STANDS FOR IRONING BOARDS

Kenneth S. Rounds and Raymond W. Gerlach,
Milwaukee, Wis., assignors to Geuder, Paeschke
& Frey Co., Milwaukee, Wis., a corporation of
Wisconsin

Application July 30, 1947, Serial No. 764,744

2 Claims. (Cl. 38—117)

1

This invention relates to improvements in latching devices for collapsible stands for ironing boards, particularly of the three-legged type.

Latch devices mounted on the front legs are utilized to hold the collapsible legs in extended board-supporting position, and upon being unlatched permit the legs of the stand to be folded. Latching devices presently used are manually unlatched. Often they stick, and considerable unlatching force is necessary. As a result of this the hands of the operator are frequently hurt or it becomes impossible for the operator to unlatch the devices.

It is an object of this invention, therefore, to provide a latching device which automatically locks the legs in extended position, and which may be unlatched either manually or by downward pressure applied by foot.

This object is accomplished by providing the usual locking link with a slotted back and sides to form space for receiving a latch pivoted to the front leg as the legs are moved to extended position. As the link moves into locking position, the latch, being spring biased upwardly, automatically engages and locks the link in such position. The latch extends beyond the front edge of the front leg and it is only necessary to press it downwardly to unlatch the link. Such pressing may be readily accomplished by foot power applied while the table is supported in upright position or manually with the table in any position.

The novel features, which are considered characteristic of the invention, are set forth with particularity in the appended claims. The invention itself, however, both as to its organization and its method of operation, together with additional objects and advantages thereof, will best be understood from the following description of a specific embodiment when read in connection with the accompanying drawing, in which:

Fig. 1 is a view in side elevation of an ironing board with collapsible legs having a latching device embodying the present invention;

Fig. 2 is an enlarged fragmentary sectional view of the latching device embodying the present invention taken on the line 2—2 of Fig. 3;

Fig. 3 is a fragmentary enlarged view taken from the line 3—3 of Fig. 2;

Fig. 4 is a fragmentary enlarged view taken from the line 4—4 of Fig. 2; and

Fig. 5 is a sectional view taken on the line 5—5 of Fig. 3.

Referring to the drawings by reference numerals, the latching mechanism is shown associ-

ated with the channel shaped front leg 10 of a collapsible three-legged stand for the ironing board 11. The front leg having two sides and a bridge, the bridge constituting the front face or edge of the leg. The rear legs 12 are connected to the front leg 10 by brace rods 13 which cause the legs to swing in unison. Locking rods 14 extending from the rear legs 12 are connected to the front leg 10 through a locking link 15. The link 15 is pivoted to the front leg 10 by the same pivot 16 which secures the brace rod 13. This much of the construction is well known. When the legs are in extended supporting position as shown in the full lines, the locking link 15 is in locking position adjacent the front leg 10. The link, when unlocked, swings away from the leg 10 to permit the legs to be swung toward folded position as is shown in the broken lines.

The locking link 15 has a back and two sides. At its upper end, the sides are spaced so that they have a sliding fit against the inner sides of the leg 10. This provides a stable bearing on the pivot 16. At its lower end, the sides are closer and snugly contain therebetween, on pivot 17, the ends of the locking rods 14. The back and sides of the locking link 15 have a slot 18 which receives the latch 19 and its pivot 20 to permit the link to swing from the unlocked position shown in broken lines to locked position within the leg 10 shown in the full lines.

The latch 19 is provided with a locking tooth 21 which engages with the upper edge of the slot 18 to lock the link 15 in the locked position. A spring 22 wrapped around the pivot 20 has a central portion bearing against the latch 19, and its ends are held in tabs 23 struck inwardly from the sides of the leg 10. The spring 22 urges the latch 19 upwardly. As the link 15 moves into the locked position, the latch is depressed until the tongue 21 slides behind the edge of the slot 18. The latch then springs upwardly to cause the tongue and edge to interlock thus holding the link 20 in locked position. It has been found preferable, but not necessary, to provide such edge of the slot 18 with a slight outward and downward taper. This facilitates the unlatching motion without in any way lessening the holding action between the latch and such edge.

In order to permit the latch 19 to be readily operated, the bridge of the leg 10 has a slot 24 through which the latch 19 projects. The bottom of the slot is low enough to permit the latch to be swung downwardly and the tongue 21 disengaged from the link 15. The top of the slot, when the link 21 is swung away from locked posi-

tion, holds the latch 19 in readiness to be received within the slot 18 and to be pressed downwardly by the action of the edge of the slot 18 riding along the slope of the tongue 21. Once the latching device is locked, it is unlocked by moving the latch 19 downwardly. This may be readily accomplished by placing the foot on the top of the projecting portion of the latch and pushing down. The bridge of the leg 10 acts as a guide for the foot and makes this movement a simple one to perform. As the unlatching occurs the weight of the table will immediately cause the legs to start to collapse moving the locking link 15 out of contact with the tongue 21. Thereafter pressure on the latch may be released and the folding of the legs completed. As the legs are swung to supporting position the link 15 will ride along the slope of the tongue 21 until it passes its locking edge. The latch 19 will then snap into the locking position under the force of spring 20 and link 15 will be automatically locking in the fully locked position. When in this position the locking rods 14 brace the legs in supporting position against any folding action.

Although only one embodiment of the invention is shown and described herein, it will be understood that this application is intended to cover such changes or modifications as come within the spirit of the invention or scope of the following claims:

We claim:

1. In a three-legged collapsible ironing board stand the front leg of which is channel-shaped having sides and a front wall within which and below the center thereof is pivotally mounted a locking link having a back and two sides, the provision of latching means for holding the locking link in extended leg locked position comprising a latch pivotally mounted in said front leg on a pivot extending between the sides of said front leg, a slot in said front wall through which said latch extends to provide a latch operating portion projecting beyond said front wall and adapted to be engaged by a foot of the operator, a spring reacting between a side of said front leg and said latch to urge said operating portion upwardly in

said slot, interlocking portions on said latch and the back of said locking link engageable when said operating portion is urged upwardly in said slot and disengageable upon downward movement of said portion in said slot, and a slot in said locking link accommodating said pivot when said link is in extended leg locked position.

2. In a three-legged collapsible ironing board stand the front leg of which is channel-shaped having sides and a front wall within which and below the center thereof is pivotally mounted a locking link having a back and two sides, the provision of latching means for holding the locking link in extended leg locked position comprising a latch pivotally mounted in said front leg on a pivot extending between the sides of said front leg, a slot in said front wall through which said latch extends to provide a latch operating portion projecting beyond said front wall and adapted to be engaged by a foot of the operator, a spring mounted on said pivot reacting between a side of said front leg and said latch to urge said operating portion upwardly in said slot, interlocking portions on said latch and the back of said locking link engageable when said operating portion is urged upwardly in said slot and disengageable upon downward movement of said portion in said slot, and a slot in the back and sides of said locking link to accommodate said latch and said pivot when said link is in extended leg locked position, the top edge of the slot in said back constituting one of said interlocking portions, said spring having a leg portion lying between said locking link and the side of said leg so as not to interfere with the positioning of said link in said locked position.
